No. 782,131.

PATENTED FEB. 7, 1905.

C. P. HEPLER.
ELECTRIC TEMPERATURE ALARM.
APPLICATION FILED FEB. 20, 1904.

UNITED STATES PATENT OFFICE.

COWAN PATTERSON HEPLER, OF SMITHTON, PENNSYLVANIA.

ELECTRIC TEMPERATURE-ALARM.

SPECIFICATION forming part of Letters Patent No. 782,131, dated February 7, 1905.

Application filed February 20, 1904. Serial No. 194,507.

To all whom it may concern:

Be it known that I, COWAN PATTERSON HEPLER, a citizen of the United States, and a resident of Smithton, in the county of Westmoreland and State of Pennsylvania, have invented 5 a new and Improved Electric Temperature-Alarm, of which the following is a full, clear, and exact description.

My invention relates to an electric alarm 10 for giving a signal when the contents of a receptacle have reached any certain predetermined temperature.

The objects of my invention are to provide 15 an alarm of the character indicated above which will be adjustable, so that it may be set for any desired temperature, which will be entirely automatic in operation, and which will be useful to a large number of different kinds 20 of manufacturers—for instance, distillers and brewers, bakers, confectioners, &c.

Reference is to be had to the accompanying 25 drawings, forming a part of this specification, in which similar characters of reference indicate corresponding parts in all the figures.

Figure 1 is a side view, partly broken away, 30 showing a tank provided with my invention. Fig. 2 is an enlarged sectional view showing the details of a preferred form of my invention. Fig. 3 is a front view of the same, and Fig. 4 is a sectional view on the line 4-4 of Fig. 3.

In the drawings, *a* represents a tank containing a boiling liquid or the like.

b shows the alarm device proper, *c* the electric connections from it, and *d* a bell by which 35 the alarm is given.

In detail my alarm device is preferably made with a flattened bulb 1, from which rises a tube 2, lined with an insulating-tube 40 3, formed of india-rubber or any desired insulating material. At the top of the tube 3 is placed a receptacle 4. The parts described constitute a receptacle for mercury or other expansive liquid, and the part 4 constitutes 45 an overflow-receptacle for the same. In the top of the overflow-receptacle 4 is placed an insulating-stopper 5, surmounted by a collar 6, which holds a rod 7, passing down through the stopper 5 and into the tube 3. This rod 50 7 is capable of being held in any adjusted po-

sition by means of the set-screw 8. In contact with the collar 6 is placed a connection 9, provided with a binding-screw 10, to which is attached a wire 11, leading to one of the outside wires *c*. 55

Upon the casing of the instrument, which is preferably made of metal, is secured a binding-post 12, which holds a wire 13, which is in connection with the other outside wire *c*. Upon the upper end of the rod 7 is a projection 14, which is designed to always be in contact with a scale 15, attached to the back of the casing. The scale 15 is preferably formed of hard rubber and provided with numerals to indicate the temperature at which it is desired to set the instrument. The projection 14 is preferably formed of spring material and is of sufficient length to come into close contact with the scale, so that it will not be easily displaced. It will be observed that the 60 rod 7, which is in connection with the parts 6, 9, 10, and 11, is entirely insulated from the casing of the instrument and from the receptacle for the mercury. The casing is preferably provided with a cover 16, secured by thumb-screws 17 and having a packing 18. 65

The operation will be obvious. When the mercury expands sufficiently to reach the rod 7, connections through the wires 11, 12, and *c* will be made to the bell *d* through a battery 80 (not shown) and cause the alarm to be given. The scale will of course be calibrated for the particular use for which the instrument is constructed. 75

The outside casing parts 1, 2, 4, 6, 7, 9, 10, 85 and 12 should be made of metal, preferably brass.

It will be obvious that many changes may be made in the construction of the apparatus without departing from the spirit of my invention as set forth in the claims, and I do not wish to be limited to the exact construction shown in the drawings. 90

Having thus described my invention, I claim as new and desire to secure by Letters Patent— 95

1. An alarm device comprising a bulb containing an expansive liquid, a tube extending therefrom, a conducting-rod extending into said tube, a projection fixed to said rod, a scale, means for adjusting said rod to fix the 100

projection at any desired point on the scale and indicate temperatures, an alarm, and electric connections from said liquid and rod to said alarm.

- 5 2. An alarm device comprising a receptacle, an insulating-lining therein, a conducting-rod extending into said receptacle, insulation between said rod and said receptacle, means for securing said rod in adjusted positions, means
10 for indicating the temperature for which the alarm is set, and electric connections from said receptacle and said rod.
3. An alarm device comprising a receptacle, an insulating-lining therein, a conducting-rod

extending into said receptacle, insulation between said rod and said receptacle, a scale of insulating material, a projection fixedly secured on said rod and adapted to rest on said scale, and means for securing said rod in adjusted positions.

20 In testimony whereof I have signed my name to this specification in the presence of two subscribing witnesses.

COWAN PATTERSON HEPLER.
